United States Patent Office

Des. 193,858
Patented Oct. 16, 1962

193,858

DROP LEAF DESK OR THE LIKE

Dave Chapman, Chicago, and Kim Yamasaki, Lombard, Ill., assignors to Brunswick Corporation, Chicago, Ill., a corporation of Delaware

Filed Nov. 28, 1961, Ser. No. 67,736

Term of patent 14 years

(Cl. D33—11)

Fig. 3.

Fig. 4.

Fig. 5.

FIG. 1 is a perspective view of a drop leaf desk or the like embodying our new design, with the drop leaf thereof in an upright position;

FIG. 2 is a perspective view thereof, with the drop leaf in a horizontal position;

FIG. 3 is a perspective view thereof, with the drop leaf in a lowered depending position;

FIG. 4 is an end elevational view thereof, taken from the end adjacent the drop leaf, with the drop leaf in a horizontal position; and

FIG. 5 is a front elevational view thereof, with the drop leaf in the horizontal position.

The dominant features of the design are shown in full lines on the drawings.

We claim:

The ornamental design for a drop leaf desk or the like, as shown and described.
